UNITED STATES PATENT OFFICE.

EPHRAIM S. HOPKINS, OF TACOMA, WASHINGTON, ASSIGNOR OF ONE-THIRD TO EMMA GRINNELL, OF TACOMA, WASHINGTON.

SASH-BALANCE.

1,256,133.

Specification of Letters Patent. Patented Feb. 12, 1918.

Application filed April 14, 1917. Serial No. 162,085.

To all whom it may concern:

Be it known that I, EPHRAIM S. HOPKINS, a citizen of the United States, residing at Tacoma, in the county of Pierce and State 5 of Washington, have invented certain new and useful Improvements in Sash-Balances, of which the following is a specification.

This invention relates to hardware, and more particularly to sash balances.

10 The object of the invention is to so construct a device of this character that it will have a maximum efficiency with a minimum cost, and by the use of which the cost of hanging windows is reduced to one-half or 15 less.

Another object is to produce a device of this character which dispenses with the use of springs, weights and cords and yet permits the window equipped therewith to 20 move easily up and down requiring the exertion of very little strength to accomplish this movement.

With the foregoing and other objects in view, which will appear as the description 25 proceeds, the invention resides in the combination and arrangement of parts and in the details of construction hereinafter described and claimed, it being understood that changes in the precise embodiment of 30 the invention herein disclosed may be made within the scope of what is claimed without departing from the spirit of the invention.

In the accompanying drawings:—

35 Figure 1 represents a front elevation of a window equipped with this improvement, parts being broken out,

Fig. 2 is a detail perspective view of one 40 end of one of the rods forming a part of this improved sash balance, and

Fig. 3 is a similar view showing a portion 45 of one of the rods and the sash carrying plug used in connection therewith.

In the embodiment illustrated, a window 50 having the usual upper and lower sash S is shown, said sash having the ordinary grooves G formed in its side edges and which ordinarily are designed to receive the cords or chains used in connection with sash balances.

The balance constituting this invention 55 comprises a pair of spirally grooved rods 1 which are exactly alike in construction and hence one only will be described in detail.

It is to be understood that each sash is

equipped with two of these rods and that the rods are concealed between the sash and the frame, being housed in the grooves G of the sash, which as above stated, are ordinarily used to house cords or chains. 60 These rods 1 extend the full length of the window frame, from the underside of the header thereof to the upper side of the sill, and their upper portions are provided with spiral grooves 2, the turns of the spirals being long or short as may be desired, nine turns of spirals being preferably employed to each six inches of rod, and when heavy windows are to be used in connection with the rods, the turns should be shorter. 70

The opposite ends of these rods 1 are mounted in metal plates 3, countersunk in the header of the frame as shown at 4 and in the window sill as shown at 5. These plates are preferably about one quarter of 75 an inch thick and an inch square and are provided with cup-like apertures or sockets 6 to receive the ends of the rod, said sockets being about three sixteenths of an inch deep so that the ends of the rods may be retained 80 in position and not rest on the wood of the frame, hence these plates perform a double function, as rod retainers and as wear plates. These plates are preferably constructed as shown in Fig. 2 with the socket 6 which receives the rod disposed close to the jamb of the window frame and they are held in position preferably by two small screws. The rods are preferably about one eighth of an 85 inch shorter than the distance between the header and the sill of the frame and are positioned for use in the manner presently to be described.

Each sash S has inserted in its opposite edges in the inner walls of the grooves thereof, two plugs as 7. These plugs are about three quarters of an inch in circumference more or less and are designed to fit in sockets in the sash to a depth of about one inch beyond the inner wall of the groove. An apertured plate 8 projects from the front end of each of these plugs 7 and is about one inch wide more or less, the aperture 9 therein being designed for the passage therethrough of one of the rods 1. This plate 8 is designed to project into the groove of the sash with its outer end disposed flush with the side edge of the sash. Each plug has a screw threaded bore 10 extending longitudinally therethrough to receive a set screw 11 110

which is disposed in said bore before the plug is inserted in the sash and one end of which projects through the front end of the bore into the aperture 9 in plate 8, as is shown clearly in Fig. 3, said end 12 being preferably rounded and adapted to extend into the spiral groove 2 of rod 1 and to facilitate the movement of the rod relatively thereto and by means of which the rod is caused to turn when the sash is moved up or down.

It will thus be seen that when the window is equipped with these rods, the sash will work freely and may be easily moved up or down and will remain in the position in which it is placed until sufficient force is exerted thereon to lower or raise it. The operation of the sash is very similar to a sash equipped with weights and yet dispenses with all of the annoyances incident to breakage and repairs of cords and weights which are ordinarily used as sash balances. Moreover, a window equipped with this invention may be hung in about one third of the time required for hanging a window using cords and weights as sash balances.

In applying these rods for use as above stated, they are preferably cut about one eighth of an inch shorter than the distance between the header and sill of the window frame to which they are to be applied, and one end of the rod is passed through the aperture 9 in plate 8 of plug 7 from the bottom up, and said rod is moved upwardly through said aperture 9 as far as the spiral. Then the top plate 3 is engaged with the upper end of the rod 1 and the sash is placed within the frame and the top plate secured by screws or in any suitable manner. The lower end of the rod is then pulled out a sufficient distance to permit the bottom plate 3 to be slipped into position and the rod is pushed inward into the groove in the sash and the plate 3 secured to the sill. It will thus be seen that the window may be hung in a very short time and when so hung, that the sash may be easily moved up and down on said rods and will remain in any posi-

tion in which they are placed until forcibly removed.

50

It will thus be seen that each window having two sashes when equipped with this invention is provided with four of the rods 1, two being employed for each sash, four of the plugs 7 and eight plates 3, and the plugs 55 7 are preferably disposed near the upper ends of the lower sash and similarly positioned on the upper sash.

From the foregoing description, taken in connection with the accompanying drawings, 60 the advantages of the construction and of the method of operation will be readily apparent to those skilled in the art to which the invention appertains and while I have described the principle of operation of the 65 invention together with the device which I now consider to be the best embodiment thereof, I desire to have it understood that the device shown is merely illustrative and that such changes may be made as are with- 70 in the scope of the claimed invention.

I claim:—

The combination with a window frame and its sash, the latter having a longitudinally extending groove in one of the side 75 members thereof and a socket extending in a plane at right angles to the plane of said groove, a plug mounted in said socket and having an apertured plate projecting therefrom into said groove, said plug having a 80 threaded bore extending longitudinally therethrough and communicating with the aperture in said plate, a screw inserted in said bore with one end projecting into said plate aperture, said end being rounded, a 85 spirally grooved rod rotatably mounted in said frame and housed in the groove of said sash and extending through the apertured plate with the rounded end of said screw engaging with said spiral groove. 90

In testimony whereof I affix my signature in presence of two witnesses.

EPHRAIM S. HOPKINS.
